UNITED STATES PATENT OFFICE

2,537,327

SPOOL WITH REMOVABLE HEADS

Harry Lovell Burbidge, Coventry, England

Application May 5, 1947, Serial No. 745,942
In Great Britain February 27, 1945Section 1, Public Law 690, August 8, 1946
Patent expires February 27, 1965

2 Claims. (Cl. 242—124)

1

This invention relates to reels, upon which yarns or other threads can be wound, for use with weaving or other textile machinery, the reels being of the kind having a hub on which there are separately attached end flanges formed of fibre-reinforced moulded synthetic resin. The object of the invention is to provide an improved reel of this kind.

According to the invention the hub of the reel is a metal tube the ends of which are externally screw-threaded, and each end flange is formed during the moulding process with an annular depression having a coacting internal screw-thread in which the respective hub end is received, the screw-threads on the hub ends being masked by the end flanges.

It is preferred that the rim of each flange should be axially proud of the rest of the external face of the flange. Thus, when two reels, according to the invention, are coaxially mounted adjacent one another, it is only the rims of the flanges which can contact one another.

The metal of the hub is preferably a light-alloy, and the ends of the hub may be locked in the flanges in any convenient manner, as by abutting the centre portions of the flanges, for axial location, and by the use of set screws to prevent the hub from un-screwing from either flange. The centre portions of the flanges preferably provide bosses extending into the ends of the hub, the bosses having in them aligned holes (to receive a supporting spindle) which are outwardly flared towards one another, to facilitate mounting the reel upon a supporting spindle.

According to a further feature of the invention, the hub is provided with a key-hole slot through which a knotted end of a length of warp or other thread can be passed, and caught thereby, when such length is to be wound on the reel.

In the accompanying drawings:

Figure 1 is a fragmentary part-sectional elevation of one form of reel according to the invention, the section being on the line 1—1 of Figure 3;

Figure 2 is an enlarged sectional detail view of the screw connection;

Figure 3 is an end elevation of the reel with part of the adjacent flange broken away; and

Figure 4 is a fragmentary cross-section through the key-hole slot in the hub.

Referring to the drawings, there are two end flanges 11 which are formed of an appropriate fibre-reinforced plastic and are moulded to shape, with recesses 13 to receive the ends of the hub 12 as hereinafter described. The bore 14 of the hub

2

is aligned with central holes 15 moulded in the end flanges.

Each end flange comprises an annular disc portion 17, a centre portion 18 to which the adjacent end of the hub is secured, a rim 19 which is usually peripherally grooved, for example, as shown at 20, and a number of radially-extending webs 21 (six in the example shown) which abut the outer face of the disc portion 17 and extend between the centre portion 18 and the rim 19. The latter, it will be observed from Figure 1, is proud, as shown at 22, on its axially-outer edge, of the rest of the flange so that when two such reels are coaxially mounted to be as close to one another as possible only their rim projections 22 will contact one another.

Each recess 13 is provided with a screw-thread round the periphery into which extends the hub, the latter having a screw-thread 24 at its ends to screw into the associated threaded recesses.

A pair of grub screws 25 is shown as passed through the centre portion 18 and engaging the end of the hub 12 to locate it against unscrewing. It is axially located by being screwed against the bottoms of the recesses.

In addition, the centre portion 18 is formed with a boss 26 extending inwardly of the adjacent end of the hub 12. The hole 15, which extends through the boss, is outwardly flared at its axially-outer end, as shown at 27, to assist in guiding a spindle when inserted through one end flange to pass through the hole 15 in the other end flange. It is preferred that the hub 12, if of an aluminum alloy, should have its surface treated so that it will not react chemically with a yarn.

Figures 1 and 4 show half a key-hole slot in the hub having a relatively-large central opening 29 connected at each end with a relatively-narrow slot portion 30 which is flared at 31 so as to provide a smooth edge to a length of thread when knotted at its end and connected with the reel, to be wound thereon, by having its knot passed through the enlarged portion 29 and then slipped down to be caught by the narrow portion 30.

The reel can be inexpensively constructed once the necessary dies for the plastic have been formed. The radial ribs 21 enable it to be formed so that it will be resistant to bending out of its plane, i. e., to warping. Screwing the ends of the hub 12 into the appropriate threaded recesses in the centre portions of the end flanges makes a very firm and satisfactory joint which also prevents any tilting of an end flange with respect to the hub.

If desired, instead of the boss 26 in an end flange being formed integrally with the centre portion, as shown, use may be made of a brass or other insert to be secured in the end flange during the moulding operation.

What I claim as my invention and desire to secure by Letters Patent of the United States is:

1. A reel, for textile machinery, comprising a tubular metal hub having external screw threads formed at its ends, and two end flanges of a fibre-reinforced plastic, each of said flanges having a rim portion extending axially beyond one face thereof which is to be the outer face, said end flanges having, on the faces which are to be their inner faces, central depressions which are peripherally bounded by screw threads which respectively receive and completely mask the screw threads at the ends of the hub when screwed fully thereto, said flanges also having on their said inner faces central bosses extending into the adjacent ends of the hub and provided centrally with coaxial holes which are outwardly flared at their ends within the hub. 15

2. A reel, for textile machinery, comprising a tubular metal hub having external screw threads formed at its ends, and two end flanges of a fibre-reinforced plastic, each of said flanges comprising an annular disc portion, and, extending axially from one face thereof which is to be the outer face, a central portion and a rim portion joined to one another and to said annular 20

5 disc portion by radially extending webs, said rim portion extending axially beyond said central portion and said webs, said end flanges having, in said centre portions, on the faces which are to be their inner faces, central depressions which are peripherally bounded by screw threads which respectively receive and completely mask the screw threads at the ends of the hub when screwed fully thereto, said flanges also having on their said inner faces central bosses extending into the adjacent ends of the hub and provided centrally with coaxial holes which are outwardly flared at their ends within the hub. 25
